UNITED STATES PATENT OFFICE.

BRAXTON L. SCOTT, OF WASHINGTON, DISTRICT OF COLUMBIA, ASSIGNOR
OF ONE-HALF TO SAMUEL SCOTT, OF NEWARK, NEW JERSEY.

OIL-FILTER.

SPECIFICATION forming part of Letters Patent No. 732,659, dated June 30, 1903.

Application filed October 2, 1902. Serial No. 125,705. (No model.)

To all whom it may concern:

Be it known that I, BRAXTON L. SCOTT, a citizen of the United States, residing at Washington, in the District of Columbia, have invented new and useful Improvements in Oil-
5 Filters, of which the following is a specification.

My invention relates to certain new and useful improvements in oil-filters, and has for its
10 object to provide a filter which shall be simple in construction and operation, which may be readily taken apart for the purpose of cleaning, and in the use of which the oil will be rapidly and thoroughly cleansed from im-
15 purities.

With these objects in view the invention re-
sides in the novel construction, combination,
and arrangement of parts hereinafter de-
scribed, and particularly pointed out in the
20 claim.

In order that my invention may be clearly
understood, I have illustrated the same in the
accompanying drawing, in which the figure
is a central vertical section of a filter con-
25 structed according to my invention.

Referring to the drawing, 1 indicates the
outer containing-tank having, as usual, draw-
off cocks 2 and 2^a and a gage 3. Within the
30 tank 1 is a receptacle 4, having a downwardly-
curved upper-edge portion 5, by means of
which it is supported from the upper edge of
the tank 1. The receptacle 4 tapers slightly
35 from top to bottom and has about the depth
relative to the tank 1, as shown. The bottom
of this receptacle is open except for a nar-
row inwardly-extending annular flange 6.
Upon this flange is supported a second recep-
40 tacle, 7, which for the purpose is provided at
its upper edge with a similar outward-ex-
tending flange 8. Said receptacle 7 also tapers
from top to bottom, is of slightly less
depth than the receptacle 4, and is provided
45 in the bottom with an outlet 9, through which
the oil may flow down into the tank 1, whence
it is withdrawn through the draw-off cock 2.
Each of the receptacles 4 7 is provided on its
inner side near the top with handles 10 11,
50 respectively, and at a suitable point above
the bottom the receptacle 7 is provided with
cleats 12. Four or more of these cleats may
be employed. These cleats are for support-

ing a disk 14 of open-work fabric, such as woven wire, which is removably seated upon said cleats. A similar disk 15 is removably seated upon the flange 8 of the vessel 7. Each 55 of said disks 14 15 is adapted to support a sack of bone-black 16 17, which sacks are of course circular in shape and of a size to fit snugly within the respective receptacles 4 7. In the upper receptacle 4 at a suitable dis- 60 tance above the sack of bone-black 16 is located a circular plate 13, having perforations 18, said plate being supported upon cleats 19, upon which it is removably seated, and hav-
ing a handle 20, by which it may be lifted out 65 of the receptacle 4. The tank 1 is provided with a cover 21, having a handle 22.

In operation oil is poured into the receptacle 4 upon the plate 13, which being perforated throughout acts as a baffle-plate to dis- 70 tribute the oil and cause it to fall over the entire surface of the upper sack 16 of bone-black. The oil percolates through this filter-
ing medium and through the disk 15 and falls upon the lower sack 17 of bone-black. Per- 75 colating through the bone-black in this latter and through the disk 14 it passes out through the outlet 9 and falls to the bottom of the tank 1. In passing through the two sacks of bone-black the oil will be thoroughly cleansed 80 from all impurities and when drawn from the tank 1 may at once be used again.

This filter is intended more especially for use in power-houses and similar places where hundreds of gallons of oil are used daily for 85 lubricating the machinery, the oil after use being collected and passed through the filter to remove from the oil all grit and impuri-
ties, so that the same oil may be used over and over again. The salient feature of the 90 invention, however, is the facility it affords for the ready removal and replacing of the filtering-receptacles and the parts supported therein, no mechanism—such as bolts, screws, or the like—being required for securing any 95 of the parts in position. As will be apparent from the drawing without further detailed description, all of the parts in the tank may be readily lifted out, either separately or all together, and as readily replaced. This op- 100 eration in practice is frequently necessary in order that the sacks of bone-black may be

boiled or otherwise treated to remove grease and impurities therefrom which have been absorbed or collected by the bone-black in the filtering operation.

5 Of course I do not limit the invention to the use of bone-black as a filtering medium, as any other suitable substance may be employed in lieu thereof.

Having thus fully described my invention, 10 what I claim as new is—

In an oil-filter, in combination with an outer tank, a receptacle having an upper curved edge portion in engagement with the upper edge of said tank and having an open bottom 15 provided with an inwardly-extending flange, a second receptacle having a flanged upper edge and supported thereby from the bottom

of the first-named receptacle and having an outlet in its bottom, supports in each of said receptacles near the bottoms thereof, an open-work disk in each receptacle mounted on said supports, a sack of filtering material supported on each of said disks, projections in the upper receptacle above the body of filtering material therein and a perforated disk mounted on said projections. 20 25

In testimony whereof I have hereunto set my hand in presence of two subscribing witnesses.

BRAXTON L. SCOTT.
